LAZY SUSAN WITH SLIDING TRAYS

Robert B. Karoff, New York, N. Y.

Application October 22, 1952, Serial No. 21,945

Term of patent 7 years

(Cl. D44—10)

To all whom it may concern:

Be it known that I, Robert B. Karoff, a citizen of the United States and a resident of New York city, county and State of New York, have invented a new, original, and ornamental Design for a Lazy Susan With Sliding Trays, of which the following is a specification, reference being had to the accompanying drawings, forming a part thereof, in which:

Fig. 1 is a perspective view of the lazy Susan with sliding trays, showing my new design, in which the sliding trays are shown in their contracted and concealed position;

Fig. 2 is a perspective view thereof in which the sliding trays are shown in their expanded or operative position and in which one of the fixed trays is shown removed for the purpose of illustration;

Fig. 3 is a front elevational view thereof in the position portrayed in Fig. 1 with the top trays and the central jar removed therefrom;

Fig. 4 is a front elevational view thereof in the position portrayed in Fig. 2, with the top trays and central jar removed therefrom;

Fig. 5 is a bottom plan view thereof in the position portrayed in Fig. 1; and

Fig. 6 is a bottom plan view thereof as shown in Fig. 2 with parts broken away for the convenience of illustration.

I claim:

The ornamental design for a lazy Susan with sliding trays, as shown.

ROBERT B. KAROFF.
